UNITED STATES PATENT OFFICE

THOMAS GRIFFITHS, OF JERSEY CITY, NEW JERSEY

WINDOW SHADE BRACKET

Application filed May 13, 1931. Serial No. 537,091.

This invention relates to improvements in window shade brackets and more particularly to shade brackets of the adjustable type.

5 The primary object of the invention resides in an adjustable shade bracket which after mounting upon a window casing may be adjusted to accommodate shades of different widths, thus the practice of shifting the usual form of shade bracket is eliminated, and which bracket results in the marring of the woodwork of a room due to the changing 10 of the position of the nails or screws.

Another object of the invention is to provide 15 an adjustable shade bracket which when in position upon the window casing and supporting a shade roller, will also act to prevent the accidental spinning of the roller when the shade is fully wound thereon which 20 results in the loss of the spring tension on the roller.

A further object is the provision of a shade 25 roller bracket which is simple of construction, inexpensive of manufacture, easy to apply to a window casing, and adjustable thereon, and which is attractive in appearance so as not to detract from the interior decoration of a room in which it may be used.

30 With these and other objects in view, the invention resides in the certain novel construction, combination and arrangement of parts, the essential features of which are hereinafter fully described, are particularly 35 pointed out in the appended claims, and are illustrated in the accompanying drawing, in which:

Figure 1 is a front elevational view of a window casing showing my invention in use.

40 Figure 2 is a perspective view of my improved shade bracket per se.

Figure 3 is an enlarged vertical sectional view on the line 3-3 of Figure 1.

45 Figure 4 is a fragmentary horizontal sectional view on the line 4-4 of Figure 3.

Referring to the drawing by reference characters, the numeral 10 designates my improved shade roller bracket in its entirety which includes an elongated base plate or 50 body 11 constructed of bendable metal and

which has its longitudinal side edges bent inwardly to form flanges 12 which are disposed in spaced relation to the body portion of the base plate to provide spaced parallel guide channels 13-13. Bent from and extending on the same side of the base plate 11 as the flanges 12, is a central rib or channel 14 which is substantially U-shaped in cross section and the bight portion of which is provided with a plurality of spaced aligned 55 openings 15 for a purpose to be presently explained. The base plate 11 is also provided with openings 16 adjacent opposite ends thereof for the passage of fastening elements when the bracket is in a mounted position 60 upon a window casing.

Slidably supported by the base plate 11 is a bracket member 17 which is provided with either a slot or opening 18 adjacent its outer end to accommodate the pintle of the shade 70 to be supported. The bracket member 17 is formed with spaced substantially L-shaped flanges 19, which flanges embrace opposite sides of the U-shaped rib 14 and portions of said flanges extend into the guide channels 13 75 and flatly abut the front side of the base plate 11.

Pivoted as at 20 between the horizontal portions of the L-shaped flanges 19 is a catch member 21 which includes a manipulating 80 head or portion 22 and an inwardly extending finger or tooth 23. A spring 24 is wound about the pivot 20 and has its ends respectively engaging the catch member 21 and the adjacent portion of the shade member 17 85 whereby the said spring tends to urge the tooth or finger 23 in a direction toward the rib 14 for engagement in any one of the openings 15. The spring permits the catch member to freely ride over the openings upon 90 movement of the bracket member in one direction but serves to hold the member in a rigid position when once adjusted, and prevents sliding movement of the member in an opposite direction unless the manipulating 95 portion 22 of the catch member is actuated.

In Figures 1 and 3 of the drawing, I have illustrated my improved shade bracket in use upon a window casing A, there being two of the adjustable shade supports or brackets 10 100

mounted upon the casing adjacent the top thereof and in horizontal alinement. Supported by the bracket 10 is a roller shade B which is provided with the usual reinforcing bar or strip C at its free end. It will be understood that the adjustable shade brackets 10 are once mounted upon the casing A, the bracket members 17 may be adjusted to accommodate the particular length of the shade roller, and after once adjusting the bracket, it is unnecessary to disturb the adjustment unless the shade is replaced by a new one and the size of the new one varies from that of the former one. In order to obtain an adjustment, it is only necessary to actuate the catch member 21 by pressing upon the manipulating head 22 to release the finger and tooth 23 from an opening 15, whereupon the member 17 may be freely slid lengthwise of the base plate 11 to the desired adjusted position.

By reference to Figure 3 of the drawing, it will be seen that the U-shaped rib 14 also acts as a stop for limiting the spinning or winding of the shade upon its roller. When the shade is fully wound, the free end carrying the reinforcing strip C will strike against the rib and prevent further winding of the roller. This stopping of the shade at its fully raised position prevents the loss of tension of the spring usually provided in shade rollers of this construction.

More specifically, the bight portion of the U-shaped rib 14 extends beyond the body 11 of the base into position for effective engagement with the reinforcing strip C of the shade so as to limit unrestrained spinning of the shade, this being admirably illustrated in Figure 3.

Although I have illustrated but one bracket member 17 as associated with a base plate 11, the said base plate may support a pair of bracket members for use in instances where a narrow dividing strip is provided in the window casing between two adjacent windows. In such instance, the one base plate 11 constitutes a support for adjustably supporting a pair of bracket members 17.

While I have shown and described what I deem to be the most desirable embodiment of my invention, it will be understood that minor changes may be resorted to as come within the scope of the appended claims.

Having thus described the invention, what I claim as new and desire to secure by Letters Patent is:

1. In a shade support, an elongated base having a central longitudinal channel member U-shaped in cross section, the bight portion of which is disposed beyond the plane of the edge portions of the base to form a shade stop, said channel member being formed with openings, a bracket flatly engaging the sides and bight portion of said channel member and having L-shaped flanges flatly con-

tacting the sides of the channel member and the edge portions of the base, and a latch pivoted between the ends thereof to said flanges and having means to extend through said openings and thereby lock the bracket in place.

2. In a shade support, an elongated base having a central longitudinal channel member U-shaped in cross section, the bight portion of which is disposed beyond the plane of the edge portions of the base to form a shade stop, said channel member being formed with openings, and a bracket flatly engaging the sides and bight portion of said channel member, and a latch pivoted to said bracket and having means to extend through said openings to secure the bracket in place.

In testimony whereof I affix my signature.

THOMAS GRIFFITHS.
